Int. Cl. D6—01

U.S. Cl. D33—14

FIGURE 1 is a perspective view of a combined table, bench and closet unit or similar article in an open position, showing my new design;

I claim:

The ornamental design for a combined table, bench and closet unit or similar article, substantially as shown and described.
